(Model.)

W. H. FULLER.

PLATE HOLDER FOR PHOTOGRAPHERS.

No. 373,231.

Patented Nov. 15, 1887.

UNITED STATES PATENT OFFICE.

WILLARD H. FULLER, OF PASSAIC, NEW JERSEY, ASSIGNOR TO THE SCOVILL MANUFACTURING COMPANY, OF NEW YORK, N. Y.

PLATE-HOLDER FOR PHOTOGRAPHERS.

SPECIFICATION forming part of Letters Patent No. 373,231, dated November 15, 1887.

Application filed July 16, 1887. Serial No. 244,488. (Model.)

To all whom it may concern:

Be it known that I, WILLARD H. FULLER, of Passaic, in the county of Passaic and State of New Jersey, have invented a certain new and useful Improvement in Plate-Holders for Photographers' Use, of which the following is a specification.

I will describe in detail a plate-holder embodying my improvement, and then point out 10 the novel features in the claims.

In the accompanying drawings, Figure 1 is a side view of a plate-holder embodying my improvement, one of the shutters being partly withdrawn. Fig. 2 is a similar view showing 15 an adjustable section or end piece of the frame in a different position. Fig. 3 is a longitudinal section taken at the plane of the dotted line $x x$, Fig. 1, and showing one of two adjustable end pieces or end sections in its normal position and the other in a reverse position. Fig. 4 is a transverse section.

Similar letters of reference designate corresponding parts in all the figures.

A designates the frame of the holder. It is 25 composed of two parallel pieces, $a' a^2$, and two intermediate pieces, $a^3 a^4$, extending at right angles to the pieces $a' a^2$. At about the center a diaphragm, a^5 , is arranged. The pieces $a^3 a^4$ of the frame I call the "end" pieces. 30 The end piece a^4 is not so thick as the other pieces of the frame, and has combined with it adjustable end pieces $a^6 a^7$, arranged one on each side of it. The end piece a^4 and the adjustable end pieces $a^6 a^7$ together approximately equal the thickness of the opposite end 35 piece, a^3 .

The pieces $a' a^2$ and the end piece a^3 are provided with grooves $a^8 a^9$, arranged one on each 40 side of the diaphragm a^5 , and the adjustable end pieces $a^6 a^7$ are provided with corresponding grooves. Sliding shutters $B' B^2$ may be fitted within these grooves. They may be inserted through the end piece a^3 , the grooves $a^8 a^9$ being extended through this end piece to 45 admit of this. The shutters are provided with hand-pieces, by which they may be manipulated.

The adjustable end pieces $a^6 a^7$ are provided at the end with tongues b , which enter grooves 50 c , formed in the opposite faces of the end por-

tions of the pieces $a' a^2$. The tongues b are provided with shoulders b' at the inner ends.

C designates bars or plates, which, as here shown, are fitted into recesses into one end of the pieces $a' a^2$. They are secured in place by 55 means of screws c . They extend across the shoulders b' of the tongues b and prevent the adjustable end pieces $a^6 a^7$ from being adjusted too far out.

Each side of the diaphragm a^5 is provided 60 with a spring, a^{10} . There is a cavity on each side of the diaphragm of suitable size for containing a photographic plate. The plates will rest against the springs of the cavities. The end piece a^3 of the frame of the plate-holder 65 is provided with flanges overlapping the cavities and adapted to secure within the same the adjacent ends of the photographic plates. The adjustable end pieces $a^6 a^7$ are also provided with flanges, and these flanges overlap and 70 secure the other ends of the photographic plates when the adjustable end pieces are in their normal positions.

To remove the plates from the holder the shutters will be moved out and the adjustable 75 end pieces moved as far outward as they are capable of being moved. Then the springs a^{10} will throw the released ends of the plates outwardly, so that they may be grasped by the fingers and taken out. When plates are to be 80 inserted in the plate-holder, the adjustable end pieces will be moved outwardly as far as possible. The plates will be introduced into the cavities of the plate-holder and extended at one end under the flanges of the end piece a^3 , 85 after which the adjustable end pieces will be moved inward and the shutters closed.

D designates a lock consisting of a button which is pivotally connected to the outer surface of the end piece a^4 , in the present instance by a screw, d , passing loosely through said button and engaging with the end piece. This button may be turned so that its length will coincide with the length of the end piece a^4 . When thus adjusted, it will not overlap 90 the adjustable end pieces $a^6 a^7$, and hence will not interfere with their adjustment. After the adjustable end pieces $a^6 a^7$ shall have been adjusted as far inward as possible, so as to 95 secure the photographic plates, the button D 100

may be turned, so as to overlap the outer surfaces of the adjustable end pieces. Then the button will retain the adjustable end pieces in the position last described. Preferably the 5 end piece a^4 will be recessed and the button fitted into the recess. When this expedient is resorted to, the outer surfaces of the adjustable end pieces will also be provided with recesses to receive the button. This construction will obviate the projection of the button beyond the end pieces a^4 a^6 a^7 .

The various pieces composing the frame of the plate-holder may be made of wood. The diaphragm of the plate-holder may be made of 15 wood or binders' board or analogous material. The shutters may be made of binders' board and provided with hand-pieces made of wood. The springs a^9 , the bars C, and the button D may be made of brass or analogous material. 20 This plate-holder may be made to contain only one plate, instead of a number of plates, if desirable. It is a very simple, cheap, and serviceable plate-holder, and withal one capable of being very conveniently manipulated. 25 What I claim as my invention, and desire to secure by Letters Patent, is—

1. In a photographic-plate holder, the combination of fixed side pieces, a fixed end piece, a sliding end piece, and a stop for limiting the extent of outward movement of the sliding end 30 piece, substantially as specified.

2. In a photographic-plate holder, the combination of fixed side pieces, a fixed end piece, a sliding end piece provided with shouldered tongues engaging with grooves in the side 35 pieces, and a stop-bar for limiting the extent of outward movement of the sliding end piece, substantially as specified.

3. In a photographic-plate holder, the combination of fixed side pieces, a fixed end piece, 40 a sliding end piece, a stop for limiting the extent of outward movement of the sliding end piece, and a lock for securing the sliding end piece in the position which it is intended normally to occupy, substantially as specified.

WILLARD H. FULLER.
